CLAIM

The ornamental design for a male connector with pogo pin contacts, as shown and described.

DESCRIPTION

FIG. 1 is a top, back, and right side perspective view of a male connector with pogo pin contacts showing our new design.

FIG. 2 is a top plan view thereof.

FIG. 3 is a left side elevational view thereof.

FIG. 4 is a front side elevational view thereof.

FIG. 5 is a right side elevational view thereof.

FIG. 6 is a back side elevational view thereof; and,

FIG. 7 is a bottom plan view thereof.
